UNITED STATES PATENT OFFICE.

EDWIN NAHR, OF LONG BEACH, CALIFORNIA.

FLOOR-MOP.

1,159,252.

Specification of Letters Patent. Patented Nov. 2, 1915.

Original application filed April 10, 1914, Serial No. 830,883. Divided and this application filed June 14, 1915. Serial No. 34,032.

To all whom it may concern:

Be it known that I, EDWIN NAHR, a citizen of the United States, and a resident of Long Beach, in the county of Los Angeles and State of California, have invented a new and Improved Floor-Mop, of which the following is a full, clear, and exact description.

The present application is a division of an application filed by me April 10, 1914, Serial No. 830,883, and it particularly relates to the means for fastening a mop cloth on a mop head.

The invention will be particularly explained in the specific description following.

Reference is had to the accompanying drawings forming part of this specification, in which similar characters of reference indicate corresponding parts in all the views, and in which:

20 Figure 1 is a front view of a mop embodying my invention, part of the handle being broken away; Fig. 2 is a longitudinal sectional elevation; Fig. 3 is a transverse sectional elevation; and Fig. 4 is a plan view of the spring fastener for the mop pad or cloth.

25 In the illustrated example, a cap or case 10 is provided adapted to receive the upper end of the mop pad 11, which is secured to the casing in the novel manner hereinafter described.

30 On the case 10 at the top are spaced angle plates 12 having feet 13 secured to the top of the case by rivets 14, or equivalent means. Plates 12 have registering bearings 15, and the ferrule 16 of the handle 17 has expansible bearing ele-

35 ments 18, 19, revoluble in the bearings 15 and frictionally held therein by a spring 20 positioned between said members 18, 19.

40 The spring is shown as coiled about a pin 21 on the ferrule 16.

The above described features form no part of the present invention, being claimed in my application above referred to.

45 In order to maintain the mop pad 11 in oiled condition for readily taking up dust, I provide a novel and effective means for the supply and even distribution of the oil. In the top of the case 10 a depression or shallow well 22 is formed at the approximate center of said case, and an orifice 23 in the case at the bottom of said well leads to the interior of the case to a distributing absorbent pad 24. The said pad 24 lies against

50 the top of the case at the under side, and is

held in position by a fastener 25 which secures the upper end of the mop pad 11. The fastener 25 consists of two resilient sections, as shown in Fig. 4. The sections are so connected as to permit of the fastener being compressed laterally against the resiliency of the sections, and also the said sections may have rockable movement relatively to each other, the connections serving to facilitate the entrance of the fastener into the case 10. I have shown the sections as each formed at one end with an eye 26 embracing the adjacent terminal of the opposite section, said adjacent terminal having a bent end 27 constituting a stop limiting the lateral expansion of the sections. The fastener 25 is placed in the interior of the pad 11, at the top, the material of the pad being gathered above said fastener, and the bunched top of the pad with the fastener 25 therein is inserted within the lower open end of the case or cap 10, said open bottom of the cap of case being defined by an inwardly projecting flange 10^a. The end of the pad is crowded between the flange 10^a and the under side of the oil pad 24, and the fastener 25 expands within the case above the flange 10^a, thereby holding the mop pad securely in position in contact with the oil pad 24.

55 The construction results in properly holding the oil pad 24 in position relatively to the mop pad, and in proper contact with the latter so that the mop pad will, by capillary attraction, take up the oil from the oil pad.

The oil-supplying features, it will be clear, result in an effective oiling of the mop pad, and the construction permits of the ready removal of the mop pad for washing, when desired.

60 The cap 10 is of oval form, being approximately elliptical, and thereby is adapted for effective use beneath furniture and in corners.

Having thus described my invention, what I claim as new and desire to secure by Letters Patent, is:

65 1. In a device of the character described, a mop head comprising a case having an oil inlet at the top and an open lower end formed with an inwardly projecting flange, an oil pad disposed in said case against the top thereof, a mop pad, and a resilient fastener within the mop pad at the upper end, 110

the said fastener being disposed above the flange of the case and holding the upper end of the mop pad against the oil pad.

2. In a device of the character described,
3. a mop head comprising a case having an open lower end formed with an inturned annular flange, a mop pad extending at its upper end within said case, and a resilient fastener at the interior of the mop and within the case and serving to bind the mop pad against the interior of said case, said fastener being formed of two sections movable relatively to each other.
13. In a device of the character described,

3. In a device of the character described,

a mop head comprising a case, and means 15 for fastening a mop pad therein, said means extending around the case at the interior and composed of two resilient sections laterally expansible and having an articulated connection with each other.

In testimony whereof I have subscribed my name to this specification in the presence of two subscribing witnesses.

EDWIN NAHR.
